[57] CLAIM

The ornamental design for a knife handle, as shown and described.

DESCRIPTION

FIG. 1 is a front perspective view of a knife handle showing my new design;

FIG. 2 is a left side elevational view thereof, the right side elevational view being a mirror image thereof;

FIG. 3 is a top plan view thereof;

FIG. 4 is a bottom plan view thereof;

FIG. 5 is a rear elevational view thereof;

FIG. 6 is an enlarged front elevational view thereof;
FIG. 7 is a left side exploded view of the knife handle on a reduced scale with portions shown in broken lines for illustrative purposes only and form no part of the claimed design; and,

FIG. 8 is a left side elevational view of the knife handle on a reduced scale in association with a broken line showing of a blade which forms no part of the claimed design.
